UNITED STATES PATENT OFFICE

THOMAS SHIPLEY, OF YORK, PENNSYLVANIA, ASSIGNOR TO YORK ICE MACHINERY CORPORATION, OF YORK, PENNSYLVANIA, A CORPORATION OF DELAWARE

APPARATUS FOR CONDITIONING AIR

Application filed September 19, 1928. Serial No. 307,010.

This invention relates to air conditioning plants for use in maintaining the desired temperature and relative humidity in enclosed spaces such as factories, theatres, and 5 other buildings in which it is necessary to maintain air at a controlled temperature and at a low relative humidity.

In my copending application Serial No. 293,072, filed July 16, 1928, I have described 10 and claimed a method of and apparatus for conditioning air, characterized by the use of a mechanical refrigerating plant in which the heat abstracted from the air of the de-humidifier is later restored in part to the 15 same air to raise its temperature and reduce its relative humidity.

In that prior structure, which was described as applied to a theatre, there was a duct leading from the theatre and back to 20 the theatre through the conditioning apparatus. There was also means for venting a portion of the vitiated air passing from the theatre and supplying make-up air from outdoors so that the air returned to the theatre 25 consisted of a mixture of recirculated and fresh air. This mixture first passed over the evaporator cooling coils of the refrigerating system where it was subjected to a washing action with chilled water. It next passed 30 through the usual eliminators and then was reheated by being passed over a portion of the condenser. This portion of the condenser may be regarded merely as a part of the condenser, but as the part in the circulating duct 35 and the part outside the circulating duct were connected in series, the first element in the duct can be regarded as the condenser pre-cooler. The advantage in this is that the refrigerant gas leaving the compressor 40 at its maximum temperature, traverses the coils in the duct, thus offering a favorable opportunity for heat transfer from the refrigerant gas to the air in the duct for re-heating purposes.

45 In the prior application the regulation of the amount of heat rejected from the pre-heater to the circulating air was effected by passing the air into contact with the pre-cooler unit of the condenser or by-passing it 50 around the same in varying proportions.

The present application is directed to a variant of this construction in which the regulation is secured in a different manner. In the present case the circulating air passes in contact with a condenser-pre-cooler at all 55 times, but the amount of heat rejected from the pre-cooler is varied by passing the hot gaseous refrigerant through the pre-cooler to the main portion of the condenser, or directly to the main portion of the condenser 60 without passing through the pre-cooler.

The success of operation is entirely dependent on a satisfactory control of the re-heating action, without unduly disturbing the condensing action of the refrigerating unit, and the structure here disclosed is believed to possess important features of utility.

The preferred embodiment of the invention is illustrated in the accompanying drawing 70 which is a diagrammatic plan view of a portion of an enclosed space such as a theatre, together with the conditioning system, shown partly in section.

A portion of an auditorium or other enclosed space is indicated at 1. From this 75 space there leads an exhaust or air discharge duct 2. 3 and 4 represent manually adjustable dampers, the damper 3 controlling the vent connection 5 leading to the atmosphere, and the damper 4 controlling flow through the duct 2. By appropriate relative settings of the dampers 3 and 4, it is possible to vent to atmosphere the desired proportion, usually about one-fourth of the total air withdrawn from the room 1. The duct 2 discharges 80 into a mixing chamber 6 into which there leads a fresh air inlet duct 7 controlled by a manually adjusted damper 8.

85 From the mixing chamber 6 the mixture of fresh and recirculated air flows to the right through a washer of known form. This includes a plurality of spray pipes 9 which are fed with spray water by a rotary pump 11, driven by a motor 12. The pump discharges through pipe 13 and draws its supply through a pipe 14 from a sump 15 into which the spray water and the water from the eliminators, hereinafter described, flow.

90 The spray water is refrigerated by evaporator coils 16, of known form, which are 100

preferably mounted in the path of the air and of the spray discharging from the spray heads 9. In this way the air is refrigerated by direct contact with the coils and also by contact with the spray water which, impinging upon the coils, is cooled as it trickles back to the sump 15. The ends of the sump are indicated at 17 and 18. 19 is an eliminator of usual construction.

10 The washer is housed in an elongated duct 21 which extends beyond the eliminators 19 and which beyond these eliminators is somewhat contracted, as shown at 22 and there encloses a set of coils 23 which has a dual function. From the standpoint of the refrigerating cycle it is a pre-cooler connected in series with the main condensing coil 24. From the standpoint of the air conditioning operation it is a re heater for raising the 20 temperature of the saturated air discharged by the eliminators 19. The main condenser 24 will ordinarily be water-cooled, but as this is familiar practice, no attempt has been made to illustrate it. The invention is not limited 25 to any particular means for cooling the coils 24.

After flowing in contact with the coils 23 the dehumidified air which is now reheated, passes to the total volume fan 25 and by this 30 fan is discharged through a return duct 26 into the theatre. The fan is driven by motor 30.

The modes of connecting the ducts 2 and 26 to the theatre or other room, may follow 35 known practice, and is not a feature of the present invention. In this connection I have in mind the known arrangements using mushrooms under the seats with either upward circulation through the theatre, or downward 40 circulation, as conditions may require. There have also been installations in which one set of ducts discharges through the side walls and the others either through the ceiling or through floor openings. My invention is 45 not limited to use with any particular system.

The discharge end of the coil 23 is connected through a check valve 27 with the inlet end of the main condensing coil 24. The check valve permits flow from the pre-cooler to the 50 condenser and closes against reverse flow.

28 represents a normally open stop valve at the inlet end of the coil 24. 29 represents a normally open stop valve at the discharge end of said coil.

55 Liquefied refrigerant flowing through the valve 29 is controlled by an expansion valve 31 which regulates the supply of refrigerant to the expander coils 16. These coils are in turn connected by the suction line 32 with the 60 compressor 33. This may be driven by an electric motor 34, in a familiar manner.

The compressor 33 discharges through the high pressure refrigerant line 34 to a switch valve 35. This valve 35 is operated by a diaphragm motor 36, and serves to connect the

line 34 either to the inlet end of the coil 23, or to the inlet end of the coil 24, or to both in varying proportions. The diaphragm motor 36 is thermostatically controlled.

For purposes of explanation, I show two thermostats 37 and 38, both connected in controlling relation to the motor 36. It is within the scope of the present invention to control the motor 36 solely by a thermostat 37, which is located in the supply duct 26. Similarly, it might be controlled solely by the thermostat 38 which is in the duct 2. This last location is the approximate equivalent of the location of the thermostat 38 within the room 1. I may use, however, an arrangement in which the control of the motor 36 is exerted primarily by the thermostat 38, and in which the thermostat 37 operates to suspend the control of the thermostat 38 and increase the reheating action of the coil 23 arbitrarily, in the event that the temperature in the duct 26 becomes too low.

The use of two thermostats, one of which suspends the action of the other, under certain conditions, is known in the temperature regulating art.

Except as expressly stated in the claims, I do not desire to be limited to any particular location for the thermostat or thermostats, but contemplate availing of known developments in the art of temperature regulation. In some cases manual regulation might be used. It is, also practicable to apply automatic regulation to dampers 3, 4 and 8, or to certain of them.

The drawing is primarily diagrammatic and no effort has been made to illustrate in detail the structure of elements which are familiar in the art and which are standard articles of commerce.

While I prefer to use carbon-dioxide as a refrigerant, and make use of a mechanical compressor, any suitable refrigerant operating on any known cycle may be substituted.

With the parts arranged as described, and with the motors 12, 30 and 34 running, the fan 25 operates as a total volume fan withdrawing air through the duct 2, chamber 6 and air washer, then through the eliminators 19 into contact with the coils 23. The air so drawn is returned through the duct 26. The proper adjustment of the dampers 4 and 3 will insure the discharge through the passage 5 of a proper proportion of the recirculated air, and the concurrent adjustment of the damper 8 will regulate the supply of a corresponding amount of fresh air to the chamber 6 at the entrance end of the washer.

In some cases it is entirely practicable to do away with the discharge duct 5 and the dampers 3 and 4, in which case the plant would operate as a plenum system and the necessary air would be vented from the auditorium by leakage, as is common practice in the art.

The refrigerating coils 16 abstract heat directly from the passing air and also from the spray, but since the spray derives whatever heat it gives up to the coils from the air, 5 the air is the ultimate source of the abstracted heat.

After passing through the washer and being deprived of a portion of its total heat, and consequently of a portion of its moisture, 10 the air passes through the eliminators 19 which serve to intercept entrained moisture. Thus the air approaches the coils 23 in a saturated condition at a low temperature and then passes in contact with the pre-cooler 15 coils 23 which reject the heat from the refrigerant to the air at a rate dependent on the setting of the valve 35. As explained this setting may be made manually or may be under the control of the thermostats 37 20 or 38, or both 37 and 38. The preferred arrangement is to control solely by the thermostat shown at 38. In this way the air is reheated in the proper degree and in its finally conditioned state is returned to the room 25 1 through the duct 26.

It will be observed that the valve 35 controls the rate of flow of gaseous refrigerant to the pre-cooler 23, and that since the check valve 27 precludes flow from the coils 24 to 30 the coils 23, there will be established in the coils 23 a pressure and temperature which will vary according to the setting of the valve 35. In this way a nice regulation of the reheating is secured.

35 The refrigerating effect of the coils 16 may conveniently be adjusted manually, and I prefer this to attempts at automatic regulation, which often introduce troublesome secondary effects.

40 The plant above described presents a number of important advantages. All the air which is discharged into the theatre has been washed and conditioned. Since all the air passes through the washer it is not necessary 45 to operate the refrigerating coils 16 at excessively low temperatures and pressures as is required in some prior systems. The resulting use of higher suction pressures increases the volumetric efficiency of the compressor and is a desirable feature.

No extraneous source of heat for reheating the air is necessary, the reheating being effected by the restoration to the air of heat units abstracted in the washer. Furthermore, 55 the cool washed air is usefully applied in preliminary cooling of hot gases, thus economizing in condenser water. Since all the air which is circulated is washed and conditioned, the total amount which need be 60 circulated to maintain a definite standard of air purity, is reduced to the possible minimum. It thus follows that the ducts and conditioning system are of smaller size than where air is by-passed to effect reheating.

65 The manner of regulating the reheating

effect by controlling the amount of hot gaseous refrigerant fed to the reheater-pre-cooler coils 23, is very effective. Not only may a nice graduation of the heat be brought about, but the action is prompt and sensitive. 70

As above stated, the showing is largely diagrammatic, and the apparatus is subject to considerable variation in the specific form of its parts. The underlying principle may be applied in various known systems of distribution, and the conditioning cycle is susceptible of automatic control of various types familiar in the art. 75

What is claimed is,—

1. The combination of a room; a ventilating duct leading from and back to said room; means for inducing a circulation through said duct; a dehumidifier unit of the refrigerating type including an evaporating cooling coil and a heat rejecting condenser, said coil and a portion only of the condenser being located in said duct in the order stated relatively to the direction of circulatory flow; and means for directing hot gaseous refrigerant at varying rates to that portion of the condenser within the duct, while the refrigerating dehumidifier continues in normal operation. 80

2. The combination of a room; a ventilating duct leading from and back to said room; means for inducing a circulation through said duct; a dehumidifier unit of the refrigerating type including an evaporating cooling coil and a heat rejecting condenser, said coil and a portion only of the condenser being located in said duct in the order stated relatively to the direction of circulatory flow; means for directing hot gaseous refrigerant at varying rates to that portion of the condenser within the duct while the refrigerating dehumidifier continues in normal operation. 85

100 3. The combination of a room; a ventilating duct leading from and back to said room; means for inducing a circulation through said duct; a dehumidifier unit of the refrigerating type including an evaporating cooling coil and a heat rejecting condenser, said coil and the first of said condenser units being located in said duct in the order stated relatively to the direction of circulatory flow; and means for directing hot gaseous refrigerant to said units in varying proportions. 105

110 4. The combination of a room; a ventilating duct leading from and back to said room; means for inducing a circulation through said duct; a dehumidifier unit of the refrigerating type including an evaporating cooling coil and a heat rejecting condenser constructed in two units connected in series, said coil and the first of said condenser units being located in said duct in the order stated relatively to the direction of circulatory flow; and means for directing hot gaseous refrigerant to said units in varying proportions. 115

120 5. The combination of a room; a ventilating duct leading from and back to said room; means for inducing a circulation through said duct; a dehumidifier unit of the refrigerating type including an evaporating cooling coil and a heat rejecting condenser constructed in two units connected in series, said coil and the first of said condenser units being located in said duct in the order stated 125

130

- relatively to the direction of circulatory flow; means for directing hot gaseous refrigerant to said units in varying proportions; and thermostatic means controlling the last named means. 5
5. The combination of a room; a ventilating duct leading from and back to the room; means for inducing a circulation through said duct; an air washer interposed in said duct; 10 means for feeding water to said washer; refrigerating means arranged to cool said water and including a heat rejecting condenser having a portion only in said duct in heat exchanging relation with air leaving the washer; and means for varying the proportion of hot gaseous refrigerant delivered to that portion of the condenser within the duct. 15
6. The combination of a room; a ventilating duct leading from and back to the room; 20 means for inducing a circulation through said duct; an air washer interposed in said duct; means for feeding water to said washer; refrigerating means arranged to cool said water and including a heat rejecting condenser having a portion only in said duct in heat exchanging relation with air leaving the washer; means for varying the proportion of hot gaseous refrigerant delivered to that portion of the condenser within the duct; and 25 thermostatic means controlling the lastnamed means. 30
7. The combination of a room; a ventilating duct leading from and back to the room; means for inducing a circulation through said duct; an air washer interposed in said duct; 35 means for feeding water to said washer; refrigerating means arranged to cool said water and including a condenser having a pre-cooler portion in said duct in heat exchanging relation with air leaving the washer, and a 40 main condensing portion not in such heat exchanging relation; and means for delivering hot gaseous refrigerant to the main condensing portion in varying proportions both directly and indirectly through the pre-cooler portion. 45
8. The combination of a room; a ventilating duct leading from and back to the room; means for inducing a circulation through said duct; an air washer interposed in said duct; 50 means for feeding water to said washer; refrigerating means arranged to cool said water and including a condenser having a pre-cooler portion in said duct in heat exchanging relation with air leaving the washer, and a main condensing portion not in such heat exchanging relation; means for delivering hot gaseous refrigerant to the main condensing portion in varying proportions both 55 directly and indirectly through the pre-cooler portion; and thermostatic means controlling the last named means. 60
9. The combination of a room; a ventilating duct leading from and back to the room; 65 means for inducing a circulation through said
- duct; an air washer interposed in said duct; means for feeding water to said washer; refrigerating means arranged to cool said water and including a condenser having a pre-cooler portion in said duct in heat exchanging relation with air leaving the washer, and a main condensing portion not in such heat exchanging relation; means interposed between the pre-cooler portion and the main portion to permit flow from the pre-cooler to the main portion and preclude back flow; and means for delivering hot gaseous refrigerant to the main condensing portion in varying proportions both directly and indirectly through the pre-cooler portion. 70
